UNITED STATES PATENT OFFICE

2,491,514

MARKING DEVICE

Ronald E. J. Nordquist, Maplewood, N. J., assignor to American Can Company, New York, N. Y., a corporation of New Jersey

Original application February 27, 1941, Serial No. 380,951, now Patent No. 2,370,184, dated February 27, 1945. Divided and this application June 28, 1944, Serial No. 542,563

8 Claims. (Cl. 101—7)

1

This invention relates to a marking mechanism for a machine for marking the end seams of cans or containers with a plurality of shallow indentations which are spaced along the end seam in such relationship as to indicate in code information as to various features such as day, month, and year in which the can was packed, the line on which the can was made on, or the line on which it was packed, or in the case of beer cans, the vat from which the beer was taken or any other desired information.

This is a division of my United States Patent Number 2,370,184, issued Feb. 27, 1945, on Can end marking machine (pending application Serial Number 380,951, filed February 27, 1941).

The marks by themselves give no information to the public and can only be de-coded or interpreted by persons having a gauge or other means of determining certain relationships. A gauge may be used, as an example, by the inspectors or officials in packing plants and can making factories so they may have a check on canned products shipped to customers. Obviously, such a gauge may be a simple means of measurement or may be a very complicated scale depending upon the complication of the marks.

The marking device comprises a series of die blocks held against endwise movement by a clamp lever and against lateral movement by the walls of a slot formed in a bracket in which they rest when in adjusted position. Each marking block is formed with a raised indenting or marking ridge which contacts the peripheral edge of the can seam as the cans roll along the positioned dies. Each block in the set denotes one code mark, as for example, one for the day, one for the month, one for the year, one for the vat, one for the line, etc.

A marking block will always have the same relative location in the assembly bracket, although blocks of like character can be interchanged as desired. For example, the day block must be changed each day, the month block changed each month, etc. Each block therefore has its marking ridge in a different position on the face. Numbered gauge marks on the bracket adjacent the position of the block facilitate placing the proper block. All of the blocks are made in the same way with gauge marks for each block on the holding bracket so that any combination of blocks may be obtained and selected to indicate in code the information it is desired to record in the peripheral edge of the can seam.

The cans are rolled over these marking blocks with a slight pressure on them so that the mark-

2

ing ridges on the blocks will be sure to make an indent in the outer surface of the can seam. The rolling of the cans is effected by a rotating turret operating in cooperation with suitable guide rails and pressure devices.

It is therefore an object of the invention to provide a marking mechanism for marking in code the peripheral edges of the can seams with spaced indents to allow one having decoding knowledge as to the relative location of the marks, to gain certain information of interest as to manufacture or filling of the cans such as the day, year, factory where the can was made, or other desirable data.

It is also an object of the invention to provide, in a marking mechanism of this type, a series of interchangeable die blocks arranged in proper order to impart the correct indents on the can seams in the desired locations.

It is a further object of the invention to provide marking devices which may be disposed along the path of rolling cans so that the seam will be marked by the ridges in the die blocks as the cans are rolled thereover.

Another object is the provision of such a marking mechanism wherein the die blocks may be clamped tightly in operating position and may be quickly released for convenient removal and replacement.

Another object is the provision of a marking device of this character wherein the die blocks are retained in a bracket which is readily movable into and out of operating position to facilitate convenient removal and replacement of the die blocks.

Numerous other objects and advantages of the invention will be apparent as it is better understood from the following description, which, taken in connection with the accompanying drawings, discloses a preferred embodiment thereof.

Referring to the drawings:

Figure 1 is a transverse vertical section of a portion of a can end seam marking machine embodying the instant invention, with parts broken away;

Fig. 2 is a sectional detail taken substantially along the line 2—2 in Fig. 1, with parts broken away;

Fig. 3 is a combined vertical section and front elevation as viewed substantially along the broken line 3—3 in Fig. 1, with parts broken away; and

Fig. 4 is a fragmentary section as taken substantially along the broken line 4—4 in Fig. 3.

As a preferred embodiment of the instant invention the drawings illustrate principal parts

of a machine embodying a marking mechanism for marking the end seams of sealed cans *a*. The cans to be marked are rolled on their sides in a horizontal position and through an arcuate path of travel through the machine by a rotatable turret *16* (Figs. 1 and 3) carried in a machine frame *17* formed with a pair of spaced upright side frames *18* between which the turret is disposed.

Turret *16* comprises a central sleeve *21* and radially extending circumferentially spaced disc-like sections or arms *22* between which turret pockets are formed. At the rear the turret sleeve *21* extends through and is journaled in the rear side frame *18*. In front the sleeve is mounted on a collar *23* which is keyed to a horizontal shaft *24*. In the front the shaft *24* is journaled in the front side frame *18* as shown at the left in Fig. 1. At the rear the shaft is journaled in a bearing (not shown) formed in the outer end of the sleeve. The shaft extends beyond the end of the sleeve and is rotated in any suitable manner.

The marking die unit, designated broadly by the numeral *27*, is located at the bottom and to the left of the turret *16* (Fig. 3) being so positioned that the peripheral seam edge of the can *a* will ride thereover and move along with the turret. Referring now to Fig. 3 some detailed consideration will be given the marking die unit *27*.

The marking unit is carried in a bracket *28* mounted on the frame base *17* and may be pushed into a marking position or pulled out to a changing position. This bracket has an arcuate top surface *29* which is concentric with the rotating turret *16* when the bracket is in place for marking. The top surface *29* of the bracket is cut away to provide an arcuate recess or slot *30* (see also Figs. 1 and 4) which slot is closed at its inner end and constitutes a seat for a series of individual die blocks *31* of the marking die unit.

The marking die blocks *31* are held against displacement by an arcuate clamping bar or ring section *32* which is disposed within a slotted seat cut into the bracket *28*, an inner face of the bar being grooved to conform to the slot *30* construction. A manually engageable pin *33* in the bar provides for easy removal of the bar when changing dies. A thumb screw *34* is threaded into the bracket *28* and holds the clamping bar *32* tightly against the die blocks *31*.

The die blocks *31* are shouldered at the bottom so that they fit the slot *30* closely and the die blocks are arranged end to end. The slot *30* terminates in a blind wall at the bottom and is open at its upper end. A clamping screw unit *35* (Fig. 3) threaded in the top of the bracket *28* at the upper end of the slot, presses down on the top or outermost die block *31* and clamps the entire end to end die assembly against longitudinal displacement.

Each die block *31* is formed with a raised suitably positioned marking ridge *36* with which the peripheral edge of the can seam engages as it moves over the die unit. The location of each die block *31* in the slot *30* indicates a particular class of the code mark. For example, the lowermost block in the end to end assembly may indicate the day on which the container was filled. The one directly thereabove may be used to indicate the month, etc.

A particular code block will always have the same position in its seat in the bracket *28* but different day blocks, for example, will have different positions of the marking ridge *36*. Obvi-

ously, for the day block there will be thirty-one different marking ridge positions. The bracket *28* preferably has a scale *37* bearing gauge marks (Fig. 4) arranged alongside the blocks to facilitate proper placing of each selected block in its assembled position.

It has been mentioned that the bracket *28* may be slid out of operative position. This is to facilitate removal and replacement of the marking blocks *31*. This sliding action is at right angles to the path of travel of the cans as they pass through the marking station (Figs. 1, 3 and 4) the bracket being mounted directly on the frame bed *17*.

The bracket *28* and the entire marking die unit are held in operative position by means of a spring pressed manually operative pin or clamping device *39*, the inner or lower end of which, as at *40* (Fig. 4) engages in a hole *41* in the frame bed. The bracket *28* slides in slotted gibs *42* (Fig. 3) bolted to the bed *17* and a stop shoulder *43* (see also Fig. 1) formed on the lower face of the bracket operates in a groove formed in the bed. This construction prevents pulling the unit off of its mounting. The bracket *28* also has an overhanging shoulder part or stop lug *44* for engagement against the front of the bed *17* to definitely locate the unit in proper marking position for the marking blocks *31* relative to the path of travel of the cans through the machine.

The cans *a* are guided endwise during their passage along the marking device by suitably formed guide rails along which the seam ends of the cans pass. Such a guide comprises an arcuate backing plate *51* (Figs. 1 and 3) which is formed with a rear ledge rail *52* and a front ledge rail *53*. The backing plate *51* at its ends is formed with lugs *54* which are anchored on tie rods *55* extending between the side frames *18*. At the front corner *40* the backing plate *51* is cut out and slotted as at *58* to provide clearance for the bracket *28* and the marking unit *27* and this leaves a front guide rail section *59* of the backing plate *51* extending alongside of the marking unit.

When the can is first delivered into the turret pocket it has no rotation on its axis. After the turret has carried it to a position over the cylindrical backing plate *51* the can drops to the plate. Thereupon it may begin to roll slowly under the urge of gravity in a free rolling motion, the wall of the turret at such time having but slight restraining effect on the rotation of the can.

The turret disc members *22* function in the usual manner as arms of a turret for the can within the turret pocket, until the can reaches a position directly beneath the shaft *24*. This is at the beginning of the marking operation and provision is made for thereafter positively rolling the can along the marking unit *27*. At the same time a slight outward pressure is applied to the front seam of the can diametrically opposite the rolling contact with the marking blocks *31*.

Three results are obtained by such a construction. The can seam is rolled over the marking ridges *36* as contra-distinguished from sliding along the dies or from being lifted by the turret. This makes clearer marks in the seam as number one result. Such a rolling of the can at the proper speed, which is slightly in excess of the speed of travel of the turret, advances the can wall forwardly of the side of the turret pocket and as number two result prevents any scratching of lithographing designs or coatings on the can wall adjacent the double seam. Finally a clearer mark 75 is obtained by pressing the can against the die

blocks, such a pressure being effected through a spring pressed floating slide ring.

The collar 23, it will be recalled, is keyed to the shaft 24 at the front of the turret 16. This collar abuts against a washer 65 (Fig. 1) which is also mounted on the shaft. Annular recess 66 is cut in the adjacent face of the collar 23 and a floating ring 67 is located in the recess. Such a ring is relatively thick adjacent its periphery but is countersunk in front to provide a tapered conical wall portion 68. The relatively thin rear portion of the ring has radial sliding movement in the recess 66. This ring is held against forward and rearward displacement by the recessed wall of the collar 23 and the rear wall of the washer 65.

The collar 23 carries four studs 69 (see also Fig. 2) which extend into radial slots 71 cut in the rear face of the floating ring 67. This construction insures uniform rotation between the collar 23, the shaft 24 and the ring but allows for the radial movement of the ring relative to the collar.

The ring 67 is formed with an outwardly extending front peripheral flange 72, the rear wall of which engages in front of the rolling can *a* on its end seam during the marking operation, as best shown in Fig. 1. This wall is disposed in alignment with the rear wall of the guide member 59 which is located in the slotted region 58 of the arcuate backing plate 51 and this member 59 also engages in front of the rolling can.

The floating ring 67 is urged downwardly on the top of the front seam of the can by a spring and roller device mounted on the forward end of the shaft 24. This device comprises a spider member 75 (Figs. 1, 2 and 3) which is loosely mounted on the rear end of a bushing 76 which in turn is mounted on the shaft 24. Such a bushing is interposed between the washer 65 and the wall of a recess 77 formed in the front side frame 18. Bushing 76 is provided with a flanged head 78 against which one end of a coil spring 79 rests. This spring is mounted on the bushing and the rear end of the spring engages against the spider 75 urging it toward the right, as viewed in Fig. 1.

The spider 75 carries four rollers 81 (see also Fig. 3) which rest within the countersunk portion of the floating ring 67 and which bear upon the tapered wall 68 of the ring. Each roller 81 is mounted on a pin 82 carried in the spider 75. The dimension of the floating ring 67 and the axial pressure exerted by the spring pressed rollers 81 are such as to hold the floating ring concentric with the shaft 24 when the ring is not engaged by the seam of the can. As soon as the can comes into engagement with the floating ring 67, it slightly lifts the ring. This engagement in point of time is just before the can rides up on the marking blocks 31. This lifting of the floating ring is very slight and any shift in position is compensated for by a yielding of the spring 79 which permits the spider 75 to slide or tilt sufficiently to allow this lifting of the ring.

It will be understood in view of this construction that pressure is applied to the seam of the can at a point diametrically opposed to the point of contact of the can seam on the marking blocks. This insures a clean cut marking action of each marking ridge 36 as the ridge is traversed by the moving and axially rotating can. The rotation of the can at such a time is such as to prevent any slippage between the seam and the marking blocks. In other words the peripheral travel of the outer surface of the can seam is equal to the linear distance on the marking blocks which is traversed by such can seam.

This construction also prevents scratching of the lithographed or otherwise coated wall of the can against the wall of the turret pocket for when the can begins to rotate on its own axis, as when it comes into engagement with the floating ring 67, it is moved by contact with the ring (Fig. 3) away from the turret pocket defining arms.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a marking mechanism for a machine for marking cans, said machine including a stationary frame and means for advancing cans therein, the combination of a stationary bracket member removably mounted in fixed position on the machine frame adjacent the path of the advancing cans, a plurality of die elements selectively carried in fixed position by said bracket member and disposed to engage and mark cans advanced thereover in the machine, movable means for holding said die elements against displacement relative to said bracket member, means for removably securing said bracket member in fixed position on the machine frame with said die elements disposed in the path of the advancing cans, and means on said frame adjacent said bracket member for guiding the movement of the advancing cans relative to said marking die elements.

2. In a marking mechanism for a machine for marking cans, said machine including a stationary frame and means for advancing cans therein, the combination of a bracket member having an arcuate slot therein mounted on the machine frame adjacent the path of the advancing cans, said slot being closed at its inner end, a plurality of die elements selectively mounted in said slot in end to end relation and disposed to engage and mark cans advanced thereover in the machine, adjustable clamping means on said bracket member engageable with the outermost of said die elements for holding said die elements against displacement relative to said slot and to said bracket member, and clamping means for removably securing said bracket member in fixed position on the machine frame with said die elements disposed in the path of the advancing cans.

3. In a marking mechanism for a machine for marking cans, said machine including a stationary frame and means for advancing cans therein, the combination of a bracket member removably mounted on the machine frame adjacent the path of travel of the advancing cans, said bracket member having an arcuate recess therein, a plurality of selective die elements mounted in end to end relation in said recess for engaging and marking cans advanced thereover, an arcuate clamping member in said recess engaging aligned portions of said die elements to prevent lateral displacement thereof relative to said recess, and movable means on said bracket member engaging an outermost die element for holding said elements against longitudinal displacement relative to said recess.

4. In a marking mechanism for a machine for

marking cans, said machine including a stationary frame and means for advancing cans therein, the combination of a bracket member removably mounted on the machine frame adjacent the path of travel of the advancing cans, said bracket member having an arcuate recess therein closed at its inner end, a plurality of selective die elements mounted in aligned end to end relation in said recess for engaging and marking cans advanced thereover, an arcuate clamping member in said recess engaging aligned wall portions of said die elements to prevent lateral displacement thereof relative to said recess, means on said bracket member for securing said clamping member in die clamping position in said recess, movable means on said bracket member engaging another wall portion of the outermost die element for holding the aligned die elements against longitudinal displacement relative to said recess, and clamping means for removably securing said bracket member in fixed position on the machine frame with the aligned die elements disposed in marking position in the path of the advancing cans.

5. In a marking mechanism for a machine for marking cans, said machine including a stationary frame and means for advancing cans therein, the combination of a bracket removably mounted on the machine frame adjacent the path of travel of the advancing cans, said bracket having an arcuate shouldered recess therein, a plurality of interchangeable marking die members each having opposed shoulders thereon arranged in end to end relation in said recess for engaging and marking cans advanced thereover, and an arcuate clamping member having a projecting shoulder thereon disposed in said bracket recess, the opposed shoulders of said die members engaging beneath the shouldered portions of said recess and said clamping member respectively, to hold said die members in marking position in said recess and against displacement relative to the bracket.

6. In a marking mechanism for a machine for marking cans, said machine including a stationary frame and means for advancing cans therein, the combination of a bracket removably mounted on the machine frame adjacent the path of travel of the advancing cans, said bracket having an arcuate shouldered recess in the upper surface thereof, said recess being closed at its inner end, a plurality of interchangeable marking die members each having opposed shoulders and indenting ridges thereon arranged in aligned end to end relation in said recess for engaging and marking code information on cans advanced thereover, an arcuate clamping member having a laterally projecting shoulder thereon disposed in said bracket recess, the opposed shoulders of said die members engaging beneath the shouldered portions of said recess and said clamping member respectively, to hold said die members against transverse displacement relative to the bracket, and clamping means on said bracket engaging the exposed surface of the outermost of said aligned die members for holding the latter against longitudinal displacement relative to said recess.

7. In a marking mechanism for a machine for marking variable code indicia upon moving cans, said machine including a stationary frame and

means for advancing cans therein, the combination of a bracket removably mounted on the machine frame adjacent the path of travel of the advancing cans, said bracket having an arcuate shouldered recess therein, a plurality of interchangeable marking die members each having opposed shoulders thereon arranged in end to end relation in said recess for engaging and marking cans advanced thereover, an arcuate clamping member having a projecting shoulder thereon disposed in said bracket recess, the opposed shoulders of said die members engaging beneath the shouldered portions of said recess and said clamping member respectively, to hold said die members in marking position in said recess against displacement relative to the bracket, and means on said bracket adjacent said die members for visually determining selective arrangement of the die members to designate variable code indicia to be marked on said cans.

8. In a marking mechanism for a machine for marking variable code indicia upon moving cans, said machine including a stationary frame and means for advancing cans therein, the combination of a bracket removably mounted on the machine frame adjacent the path of travel of the advancing cans, said bracket having an arcuate shouldered recess in the upper surface thereof, said recess being closed at its inner end, a plurality of interchangeable marking die members each having opposed shoulders and indenting ridges thereon arranged in aligned end to end relation in said recess for engaging and marking code information on cans advanced thereover, an arcuate clamping member having a laterally projecting shoulder thereon disposed in said bracket recess, the opposed shoulders of said die members engaging beneath the shouldered portions of said recess and said clamping member respectively, to hold said die members against transverse displacement relative to the bracket, clamping means on said bracket engaging the exposed surface of the outermost of said aligned die members for holding the latter against longitudinal displacement relative to said recess, and means on said bracket adjacent said die members for visually determining selective arrangement of the die members to designate variable code indicia to be marked on said cans.
